UNITED STATES PATENT OFFICE.

HILLIARD N. A. McLEAN, OF DETROIT, MICHIGAN.

SANITARY CLOSET.

1,207,188.

Specification of Letters Patent.

Patented Dec. 5, 1916.

Application filed February 8, 1915. Serial No. 6,731.

11 *To all whom it may concern:*

Be it known that I, HILLIARD N. A. McLEAN, a citizen of the United States of America, residing at Detroit, in the county 5 of Wayne and State of Michigan, have invented certain new and useful Improvements in Sanitary Closets, of which the following is a specification, reference being had therein to the accompanying drawings.

10 The invention relates to sanitary closets and has among the objects thereof to provide a construction in which the seat may be easily and quickly cleaned; to provide a construction in which the cleaning of the 15 seat will be automatically accomplished; to provide a structure in which the surface of the seat is subjected to a cleaning fluid and then automatically dried.

Other objects of the invention will more 20 fully hereinafter appear.

The invention resides in the peculiar construction, arrangement and combination of parts as will be hereinafter set forth.

In the drawings, Figure 1 is a perspective view of a closet embodying the invention; Fig. 2 is a longitudinal section showing the seat in one position of adjustment; Fig. 3 shows the parts in a different position of adjustment; Fig. 4 is a section on the line 30 $x-x$ of Fig. 2; Fig. 5 illustrates a certain relation of parts; Fig. 6 is a top plan view; Fig. 7 illustrates a modification; and Fig. 8 is a section through the controlling valve.

A designates the bowl of the closet, and B 35 the seat. The latter is herein shown as composed of a frame C in which are mounted members D and E that form the seat proper. These members are mounted to be turned so as to allow different portions of their surfaces to be exposed at the top, and suitable 40 mechanism is provided for cleaning the surfaces of the members D and E. The latter are herein illustrated as composed of rolls each carried by a shaft F, the ends of which 45 are journaled in the ends G and H of the seat frame C. Preferably the frame C is formed of a metallic strip arranged on edge except at the front of the bowl, where it is turned downwardly, as shown in Fig. 1. The 50 frame C is provided with rearwardly-extending arms I that are hinged to brackets J on the bowl, and the front of the frame C is normally held slightly raised from the bowl by means of springs D² on the hinged connection between the seat frame and the bowl.

These springs are of proper tension to allow the seat to be readily depressed until the frame C rests upon the upper edge of the bowl, as shown in Fig. 5.

For cleaning the seat I preferably subject 60 the surfaces of the rolls to a cleaning liquid and then dry the roll surfaces. In the one embodiment of the invention illustrated in Figs. 1 to 5 inclusive, the frame C carries pipes L having perforations M arranged to 65 spray liquid upon the roll surface. These pipes are respectively arranged upon the inner sides of the rolls and at their rear ends are connected by a swiveled joint N with the supply pipe O. Controlling the 70 supply pipe O is a valve P shown herein as of the ported rotary type (see Fig. 8). This valve is connected to a shaft Q, has its outer end arranged in a bracket R, and also carrying an arm S.

T is a bell-crank lever fulcrumed at U upon a bracket on the bowl and having one arm slotted at V to engage a pin W on the frame C.

X is a spring having one end connected to 80 a pin Y fixed upon the bowl and having the other end attached to a pin Z on the lever S. This spring tends to normally hold the lever S in the position shown in Figs. 2 and 3, and the valve in this position is as illustrated in 85 Fig. 8.

As will be noted from Fig. 8, the port A' in the valve proper B'—when the valve is closed—has one end thereof but slightly out of registration with the port C' in the valve 90 casing. By this arrangement, when the seat rises, the inwardly-extending arm D' of the lever T which is above the member S—as shown in Fig. 3—will contact with the member S and immediately open the valve 95 B'. When the seat is in its raised position, as shown in Fig. 2, the arm S has passed out of engagement with the inwardly-extending portion D' of the lever T, allowing the spring X to close the valve. However 100 with the parts shown in Fig. 2, when the seat is depressed the arm S will be raised, but because of the relation of the port A' to the port C' in the normal position of the valve B', a sufficient upward movement 105 of the arm S will be permitted, to allow the extension D' to pass by the arm S without opening the valve.

In order to allow the surfaces of the rolls to be cleaned, the latter are rotated so that 110

during the time the liquid is sprayed upon the rolls, the roll surfaces or portions thereof are cleaned. In the structure shown, this is accomplished by providing each roll with a pinion E' that engages a stationary rack F' which is secured to the bowl. The racks F' may be fastened to the bowl in any desirable manner as by means of a metallic strip or frame G' adapted to fit over the front of the bowl and to which the racks F' are rigidly connected. Preferably it is desired to turn the rolls during the upward movement of the seat, but to have the rolls remain stationary during the depression of the seat. This is accomplished by connecting the pinion E' , through the medium of a ratchet mechanism I' , to a member H' that is fixed to turn with the roll but is free to rotate upon the shaft.

10 The drying of the roll surfaces is accomplished by means of wipers L' and J' pivoted to brackets K' carried by the frame C and having the outer ends thereof yieldably held into engagement with the rolls by means of springs M' . Preferably the arrangement is such that the rolls are turned substantially half a revolution when the seat is raised from the position shown in Fig. 3 to the position shown in Fig. 2. Because of the 15 relation of the parts, if it is desired, the frame C and all the mechanism thereon may be raised as a unit to allow access to the bowl.

20 Instead of spraying the liquid upon the rolls, other forms of washing the rolls may be employed, and as shown in Fig. 7, another novel and simple manner of accomplishing this result is illustrated. Thus N' are receptacles carried by the bowl and of a 25 length substantially equal to the rolls. These receptacles are arranged to allow the rolls to be partially immersed in the liquid therein when the seat is down, but when raised the rolls are completely out of the liquid. In the structure shown in Fig. 7, 30 the mechanism for turning the rolls may be accomplished as hereinbefore described, but the valve operating mechanism and the spray pipes are omitted.

35 While I have shown and described the particular structures illustrated in the drawings, I do not wish to limit the protection to these embodiments of the invention, since it will be readily appreciated that the invention

is capable of being used with various specific structures.

What I claim as my invention is:—

1. In a closet, the combination with a seat proper composed of rotating portions, of means for subjecting the rotating portions to a cleaning fluid, and wipers extending longitudinally of said rotating portions and yieldably held in engagement therewith.

2. In a closet, the combination with a bowl, of a seat comprising a frame, spaced members mounted in said frame to turn, means for subjecting said members to a cleaning fluid, wipers extending longitudinally of said members and yieldably held in engagement therewith, pinions carried by said rolls and stationary racks upon the bowl engaging said pinions, and means for connecting the pinions to their respective members in one direction of movement of the pinions only.

3. In a closet, the combination with a bowl, of a seat proper composed of coacting rotating portions, of means intimately associated with each of said portions above said bowl for spraying the same.

4. In a closet, the combination with a seat proper mounted to undergo a slight up and down movement and including rotating portions, of means for moistening said portions, and means for automatically rotating said portions during its slight upward movement, said portions being stationary during the downward movement.

5. In a closet, the combination with a seat comprising a frame mounted to undergo a slight up and down movement and a pair of parallel rollers mounted in said seat, of a mechanism utilizing said movement of said frame to actuate a simultaneous rotation of the rollers, means for discharging a liquid upon said rollers, and a valve controlling the supply of liquid to said discharge means, normally closed, automatically opened by a displacement of said frame and automatically closing as said displacement is completed.

In testimony whereof I affix my signature in presence of two witnesses.

HILLIARD N. A. MCLEAN.
